SPARK PLUG WITH VISUAL INDICATING
DISCHARGE BULB

Alfred Candelise and John A. Whaley, Flint, Mich., assignors to General Motors Corporation, Detroit, Mich., a corporation of Delaware

Filed Aug. 15, 1962, Ser. No. 217,086
3 Claims. (Cl. 313—1)

This invention relates to spark plugs for internal combustion engines, and more particularly to a spark plug adapted to be a visual indicator for its own sparking operation.

A function of the device is to eliminate the customary spark test which is made by disconnecting the high tension cable from the plug and causing a spark between the cable and cylinder block by cranking the motor.

In the past, indicators have been designed for the purpose of detecting spark plug operation and have taken the form of pencil-like units containing a neon bulb which may be viewed through a window when the device is electrically connected with the spark plug electrodes. Such a device is disclosed in U.S. Patent 1,957,802. In the case of the pencil-like tester, the inconvenience of carrying about an auxiliary test device out weighs the possible advantages it may have. Furthermore, the disadvantage of having to locate the viewing window in the line of sight of the observer has defeated attempts at its wide use. For these reasons, a new approach was needed.

It is known that high production spark plugs have relatively thick, opaque insulators. These insulators are designed primarily for their insulative properties and may vary in chemical composition and structure depending on the use of the spark plug. It is now proposed to provide a spark plug the insulator of which being manufactured so that portions thereof become translucent whereby the spark plug serves as its own visual indicator of spark delivery and without adversely affecting the normal function of such insulators.

In accordance with the invention, a spark plug having a ceramic insulator provided with translucent wall portions and comprising at least 85 percent alumina is adapted to receive a light source totally concealed therewithin. The light source is electrically energizable and adapted to be connected in series with the spark plug electrodes and when a sparking voltage is applied thereto, the light source is energized illuminating the translucent wall portions producing a glow to indicate to an observer the presence of high voltage at the plug.

It is a purpose of the present invention to overcome the disadvantages of the pencil-like tester by the use of the novel insulator which enables an observer to detect the presence of energy at the plug regardless of the position of the insulator with respect to the observers line of sight and regardless of whether the device is used during daylight or darkness.

These and other objects will appear by reference to the following description and drawing.

Referring to the drawing in detail, the spark plug 10 is represented by a longitudinal sectional view and is equipped with a conventional metal shell 12 having threads 14 for threadably mounting the spark plug in an engine. Positioned within the metal shell 12 and secured in the conventional manner is an insulator 16. The insulator is of a ceramic material composed of at least 85 percent alumina and may be glazed or unglazed depending upon the wishes of the user. The insulator 16 is formed with a center bore using a lower portion 18 of relatively small diameter, a center portion 20 of larger diameter, and a top portion 22 of still larger diameter which serves as a well for receipt of a suitable light source 24 herein illustrated for convenience as a neon lamp hav-

ing electrode leads 26 projecting into the neon atmosphere and extending from opposite ends and being sealed by the glass bulb 28; the leads being bent to lay against the surface of the glass bulb 28 to establish electrical contact as hereinafter described. In the lower portion 18 of the insulator is positioned a metallic electrode 30 having a serrated tip. The electrode center element 32 is sealed in the center portion 20 of the insulator and connects with electrode 30 through a conductive glass seal 34. Coned coil springs 36 receive the tapered ends of the bulb 28 and electrically contact the leads 26.

The bulb 28 is biased by the springs 36 axially in a floating position approximately midway within the upper portion 22 of the insulator body. The springs 36 bear 15 against the terminal 38 in one case and against the top of the electrode center element 32 in the other, thus establishing an electrical path from the terminal 38 to the serrated tip of the center electrode 30. The ground electrode 40 is attached to the metal base 12 and spaced 20 from the serrated tip of the center electrode 30 to establish a firing gap in the well-known manner. The springs 36 also have an important safety function. Should the bulb 28 accidentally be broken, the operation of the plug will not be affected. That is, the plug will continue to operate in the manner of a conventional spark gap plug in that the spark will jump across the gap at the springs. This will not occur when the bulb 28 is in position because the electrical path established by the neon lamp electrode leads 26 is of lesser electrical resistance 25 than that of the gap between springs 36.

It is to be understood that the insulator 16 is of a special construction as will hereinafter appear. It is known that spark plug insulators are formed of a relatively high alumina ceramic material providing electrical insulation between the center wire electrode and the metal base of the spark plug. Such insulators must function 35 in all the ways conducive of efficient spark plug operation. These requirements, it is assumed, are well-known to those skilled in the art. The present invention is concerned with providing an insulator meeting the above requirements but in addition, providing one having the property of translucence, a property, to our knowledge, heretofore never directly associated with spark plug insulators. This physical property has been taken advantage of in the present invention.

Accordingly, we have found that if the chemical composition of the ceramic material that goes into the insulator has an alumina content in excess of 85 percent and if insulator wall portions are molded with zones of relatively thin cross section as shown by the circular rings 42 formed in the walls of insulator 16; then a light source of normal intensity situated within such an insulator will send light through the walls becoming visible uniformly to an observer from without. For example, an observer looking at the insulator 16 during the operation of the plug would see a high-frequency flutter or glow at the circular depressions or rings 42. Such a glow would naturally be more apparent during the hours of darkness. However, the preferred embodiment of the invention as 50 illustrated compensates for the loss in contrast during the hours of daylight by providing for shadow casting projections or shoulders 44 which increase the illumination effect at the glow rings 42.

In most cases, the alumina content should be as high 55 as possible and at least in excess of 85 percent alumina. The wall thickness at the rings 42 should, of course, be as thin as possible and still satisfy the engineering requirements of a spark plug insulator. That is, depending upon the particular engine and the type of plug, the insulator thickness in these regions will be designed to provide for maximum translucency under the circumstances. For satisfactory viewing, the current flowing through the neon

lamp is in the range of 2 to 15 milliamperes and the insulator thickness is in the range of .03 to .06 inch.

Although the invention has been described with reference to the particular embodiments shown, it is not to be so limited since changes and alterations therein may be made which are within the full and intended scope of the claims which follow.

We claim:

1. A spark plug comprising a metal base; an insulator body adapted to receive a light source mounted on said base and formed of a ceramic material comprising at least 85% alumina, said insulator body having wall portions sufficiently thin to become translucent, said insulator having a stepped centerbore; a first electrode connected to said base; a second electrode insulated from said base by said insulator and spaced from said first electrode; a terminal mounted on the top of said insulator and having the lower portion thereof extending into the insulator centerbore; a glow discharge bulb of the rare gas type positioned in said centerbore, said bulb normally providing an electrical series path between said second electrode and said terminal whereby a voltage supplied across said first electrode and said second electrode that is sufficient to produce an electrical spark therebetween will simultaneously energize said glow discharge bulb sending visible light through said translucent wall portions to indicate spark plug operation; and electrode means associated with said bulb operative to establish an auxiliary spark gap in said insulator when said bulb is inoperative thereby enabling said spark plug to continue to operate.
2. A spark plug comprising a metal base; an insulator body adapted to receive a light source mounted on said base and formed of a ceramic material comprising at least 85% alumina, said insulator body having wall portions sufficiently thin to become translucent, said insulator body having a stepped centerbore; a first electrode connected to said base; a second electrode insulated from said base by said insulator and spaced from said first electrode; a terminal mounted on the top of said insulator and having the lower portion thereof extending into the insulator centerbore; a glow discharge bulb of the rare gas type positioned in said centerbore and having an upper electrode lead sealed thereto projecting from the upper end of said tube and a lower electrode lead sealed thereto projecting from the lower end of said tube; said upper lead and said lower lead bent to lay against the surface of said bulb so that the ends of said leads face each other; an upper coil spring positioned about the upper end of said bulb and in electrical contact with said upper electrode lead, said upper spring being in electrical contact with the said terminal; a lower coil spring positioned about the lower end of said bulb and in electrical contact with said lower lead, said lower coil spring being in electrical contact with said second electrode; said bulb normally providing an electrical series path between said second electrode and said terminal whereby a voltage supplied across said first electrode and said second electrode that is sufficient to produce an electrical spark therebetween will simultaneously energize said glow discharge bulb sending visible light through said translucent wall portions to indicate spark plug operation; and said springs cooperating to establish an auxiliary spark gap between said upper lead and said lower lead when said bulb is inoperative thereby enabling said spark plug to continue to operate.

electrical spark therebetween will simultaneously energize said glow discharge bulb sending visible light through said translucent wall portions to indicate spark plug operation; and means including said springs being operative to establish an auxiliary spark gap when said bulb is inoperative thereby enabling said spark plug to continue to operate.

3. A spark plug comprising a metal base; an insulator body adapted to receive a light source mounted on said base and formed of a ceramic material comprising at least 85% alumina, said insulator body having wall portions sufficiently thin to become translucent, said insulator body having a stepped centerbore; a first electrode connected to said base; a second electrode insulated from said base by said insulator and spaced from said first electrode; a terminal mounted on the top of said insulator and having the lower portion thereof extending into the insulator centerbore; a glow discharge bulb of the rare gas type positioned in said centerbore and having an upper electrode lead sealed thereto projecting from the upper end of said tube and a lower electrode lead sealed thereto projecting from the lower end of said tube; said upper lead and said lower lead bent to lay against the surface of said bulb so that the ends of said leads face each other; an upper coil spring positioned about the upper end of said bulb and in electrical contact with said upper electrode lead, said upper spring being in electrical contact with the said terminal; a lower coil spring positioned about the lower end of said bulb and in electrical contact with said lower lead, said lower coil spring being in electrical contact with said second electrode; said bulb normally providing an electrical series path between said second electrode and said terminal whereby a voltage supplied across said first electrode and said second electrode that is sufficient to produce an electrical spark therebetween will simultaneously energize said glow discharge bulb sending visible light through said translucent wall portions to indicate spark plug operation; and said springs cooperating to establish an auxiliary spark gap between said upper lead and said lower lead when said bulb is inoperative thereby enabling said spark plug to continue to operate.
